UNITED STATES PATENT OFFICE.

AGNES S. ADAM, OF WASHINGTON, DISTRICT OF COLUMBIA.

DESIGN FOR A GARMENT-SUPPORTER.

43,030.

Specification for Design.

Patented Sept. 24, 1912.

Application filed May 14, 1912. Serial No. 697,338. Term of patent 7 years.

To all whom it may concern:

Be it known that I, AGNES S. ADAM, a citizen of the United States, residing at Washington, in the District of Columbia, have invented a new, original, and ornamental Design for Garment-Supporters, of which the following is a specification, reference being had to the accompanying drawing, forming part thereof.

Figure 1 is a view in front elevation, Fig.

2 is a view in rear elevation, and Fig. 3 is a view from one end.

I claim:

The ornamental design for a garment supporter, as shown.

AGNES S. ADAM.

Witnesses:

J. D. YOAKLEY,
VERNON E. HODGES.
